UNITED STATES PATENT OFFICE.

LEE J. BLACK, OF BEAUMONT, TEXAS.

CONDENSER PIPE.

Application filed May 13, 1926. Serial No. 105,928.

This invention relates to condenser pipes and more particularly to condenser pipes of the type employing internal corrugations for breaking up the vapor stream within the pipe to prevent passage through the pipe of a core of uncondensed vapor which has not come in contact with the walls of the pipe.

An important object of the invention is to produce a device of this character having a plurality of drainage pairs wherein the inner walls of the pipe is straight, preventing pocketing of the condensed fluids, these drainage pairs corresponding in number and arrangement to the facets of the pipe flange so that any particular facet may be upwardly disposed and still a proper drainage path provided.

A further object of the invention is to produce a device of this character which may be readily manufactured and in which a maximum radiation surface is provided.

These and other objects I attain by the construction shown in the accompanying drawings, wherein for the purpose of illustration is shown a preferred embodiment of my invention and wherein:—

Figure 1 is an end elevation of a condenser pipe constructed in accordance with my invention;

Figure 2 is a fragmentary side elevation thereof;

Figure 3 is a section on the line 3—3 of Figure 1;

Figure 4 is a section on the line 4—4 of Figure 2;

Figure 5 is a section on the line 5—5 of Figure 4.

Referring now more particularly to the drawings, the pipe consists of alternate polygonal and round sections 10 and 11, the sections 10 being in the present illustration disclosed as rectangular. These sections may be made with any suitable number of sides, but the number of sides employed should correspond with the number of sides upon the coupling flange 12 provided at the end of the pipe. The internal diameter of the round sections 11 is the same as the inscribed diameter of the polygonal sections 10 so that a section taken along sections of the corresponding sides of the polygonal sections will provide a straight flat wall 13 upon the interior of the pipe along which fluids may travel. It will, of course, be understood that a polygonal section having an even number of sides must be employed,

so that when an upper facet 14 of the flange is horizontally arranged, a diametrically opposed lower facet 15 is likewise horizontally arranged.

The interior angles 16 between adjacent sides of the rectangular section are rounded, as illustrated, so that no pocket is formed in which condensed fluids will tend to collect and so that all of these condensed fluids will be directed toward the path provided at the bottom of the pipe for their passage. The perimeter of each rectangular section is formed with a projecting rib or vane 17 to increase the cooling surface provided. It will be noted that in alignment with the corresponding included angles of the polygonal sections a sinuous wall 18 is produced which will tend to keep the passing vapors in continuous motion to break up the core of the vapor stream. There will be walls 18 corresponding in number to the included angles 16 of each polygonal section and their combined action upon the vapor stream will tend to very thoroughly break the stream up, bringing all parts of the vapor into contact with the walls of the pipe.

It will, of course, be understood that in referring to rectangular and round sections, reference is had to the construction of the interior of the pipe, as the exterior wall thereof may be of any desired conformation. This exterior wall, however, preferably corresponds in contour to the interior construction of the pipe.

Since certain other changes are possible in the construction hereinbefore set forth without departing from the spirit of my invention, I do not limit myself to such specific structure except as hereinafter claimed.

I claim:—

1. A condenser pipe formed interiorly to produce alternate round and polygonal sections, the polygonal sections having corresponding sides thereof disposed in common planes tangential to the round sections whereby the round and polygonal sections combine to produce wall sections corresponding in number to the sides of the polygonal sections in which the points of tangency and the mid-points of the corresponding sides of the polygonal sections lie in the same straight lines.

2. A condenser pipe formed interiorly to produce alternate round and polygonal sections, the polygonal sections having corresponding sides thereof disposed in common

- planes tangential to the round sections whereby the round and polygonal section combine to produce wall sections corresponding in number to the sides of the polygonal sections in which the points of tangency and the mid-points of the corresponding sides of the polygonal sections lie in the same straight lines, the exterior of the pipe being provided in alignment with each polygonal section with an outstanding cooling rib.
- 10 3. A condenser pipe formed interiorly to produce alternate round and polygonal sections, the polygonal sections having corresponding sides thereof disposed in common planes tangential to the round sections whereby the round and polygonal sections combine to produce wall sections corresponding in number to the sides of the polygonal sections in which the points of tangency and the mid-points of the corresponding sides of the polygonal sections lie in the same straight lines, the exterior of the pipe being provided in alignment with each polygonal section with an outstanding cooling rib.
- 15 4. A condenser pipe formed interiorly to produce alternate round and polygonal sections, the polygonal sections having corresponding sides thereof disposed in common planes tangential to the round sections whereby the round and polygonal sections combine to produce wall sections corresponding in number to the sides of the polygonal sections in which the points of tangency and the mid-points of the corresponding sides of the polygonal sections lie in the same straight lines, the exterior of the pipe being provided in alignment with each polygonal section with an outstanding cooling rib.
- 20

in the same straight lines, the included angles between adjacent sides of said polygonal sections being rounded.

4. A condenser pipe formed interiorly to 25 produce alternate round and polygonal sections, the polygonal sections having corresponding sides thereof disposed in common planes tangential to the round sections whereby the round and polygonal sections 30 combine to produce wall sections corresponding in number to the sides of the polygonal sections in which the points of tangency and the mid-points of the corresponding sides of the polygonal sections lie in the same 35 straight lines, the connections between those portions of the cylindrical and polygonal sections lying between said points providing a sinuous wall.

In testimony whereof I affix my signature.

LEE J. BLACK.
